Primary Examiner — Mary Ann Calabrese*Assistant Examiner* — Sloan Rozin(74) Attorney, Agent, or Firm — Hogan Lovells US LLP(57) CLAIM

The ornamental design for a dressing table, as shown and described.

DESCRIPTION

FIG. 1 is a perspective view of a dressing table showing the design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The broken lines showing portions of the bottom features of the dressing table are included for the purpose of illustrating environment and form no part of the claimed design.
